Primary Examiner — Sheryl Lane*Assistant Examiner* — Calvin E Vasant*(74) Attorney, Agent, or Firm* — Crowell & Moring LLP(57) **CLAIM**

The ornamental design for a vehicle wheel, as shown and described.

DESCRIPTION

FIG. 1 is a perspective view of a vehicle wheel according to the design;

FIG. 2 is an additional perspective view thereof;

FIG. 3 is an additional perspective view thereof;

FIG. 4 is a front view thereof;

FIG. 5 is a rear view thereof; and,

FIG. 6 is a side view thereof.

The low contrast or “ghost” areas of the drawings depict portions of the vehicle wheel that form no part of the claim.
